ADJUSTABLE CYLINDER LOCK MECHANISM

Samuel Oxhandler, Flushing, N. Y., assignor to
Sargent & Company, New Haven, Conn., a corporation of Connecticut

Application December 9, 1943, Serial No. 513,544

6 Claims. (Cl. 70—374)

This invention relates to locks, and more particularly to an adjustable cylinder lock constructed of a number of elements of such form and arrangement that various selected elements may be employed to provide locks of different sizes and of different types.

In the use of cylinder locks, and particularly pin tumbler locks, it is necessary to provide a number of different kinds and sizes of cylinders for various lock applications. For example, doors with which the locks are used vary in thickness, and it is desirable to use cylinders of various lengths so that the outer face plate of the cylinder will be substantially flush with the door or with an escutcheon mounted upon the door. Also, depending upon the type of lock with which the cylinder is used, it is often necessary to vary the construction of the inner end of the cylinder. For example, in connection with mortise locks a rollback is usually secured to the key barrel to be operated thereby, while in connection with so-called night latches and other types of locks a spindle, either square or flat, is connected to the key barrel.

I contemplate by the present invention the provision of a cylinder lock, and more specifically a pin tumbler lock, having a housing or casing within which the tumbler mechanism and key barrel are mounted, which structure will be the basic element of the lock. Other elements are provided which may be applied in various combinations to the basic structure just described, to build locks of various forms and sizes.

One object of the present invention is to provide a cylinder lock constructed of a plurality of detachable or separable elements some of which may be selectively used in building the completed lock.

A further object of the invention is to provide a cylinder lock mechanism having a basic structure comprising a housing, tumbler mechanism, and a key barrel, and also comprising a plurality of selectively attachable elements whereby a plurality of locks of different types and sizes may be built upon the basic structure.

A still further object of the invention is to provide a cylinder lock which may be adjustable as to length by the employment therein of one or more spacer members between front and rear detachable sections, the front section containing the tumbler mechanism and the rear section having a rollback detachably carried thereby.

To these and other ends the invention consists in the novel features and combinations of parts to be hereinafter described and claimed.

In the accompanying drawing:

Fig. 1 is a front plan view of a cylinder lock embodying my improvements;

Fig. 2 is a side elevational view of one form of lock;

Fig. 3 is a rear view of the lock shown in Fig. 2;

Fig. 4 is a sectional view on line 4—4 of Fig. 1;

Fig. 5 is a sectional view on line 5—5 of Fig. 2;

Fig. 6 is a view similar to Fig. 4 but showing a lock of greater length;

Fig. 7 is a view similar to Fig. 2 but showing the lock adapted for the operation of a spindle;

Fig. 8 is a rear view of the lock shown in Fig. 7;

Fig. 9 is a rear view of the basic structure or front section of the lock; and

Figs. 10 to 14 are detail views of various elements of the lock.

To illustrate a preferred embodiment of my invention, I have shown in the drawing a cylinder lock, which in this instance is a pin tumbler lock, comprising a main body portion 10, which I term the basic structure of the lock, as this portion contains the pin tumbler mechanism 11 of usual form, and also has rotatably mounted therein a key barrel 12. The key barrel 12 is adapted to be inserted into the casing 10 from the front portion thereof, and is provided with a head 13 on its front end. Secured to the rear end of the key barrel by screws 14 is a disk-shaped member 15, which member, as will be apparent from Fig. 4, is larger in diameter than the key barrel, so that, when it is secured to the key barrel, the latter will be effectively retained in place by this disk and the head 13. As shown more especially in Figs. 2 and 5, the walls of the body 10 may be cut away at the sides, as at 16, leaving a cylindrical portion 17 at the rear end of the part 10.

As illustrated in Figs. 1 to 5 of the drawing, there is secured to the casing or body portion 10 of the lock a rear section 18. As will be explained hereinafter, this rear section may be made up of a plurality of parts, depending upon the length which is desired in the completed cylinder. As shown in these figures of the drawing, the section 18 consists of a single part having external threads 18a by which it may be secured to a bolt casing, and is provided with an opening 19 to receive rotatably the hub 20 of a rollback 21. The rollback is secured to the disk 15 by screws 22, which pass through the rollback and also through its hub 20.

The section 18 is secured in place by means of screws 23 which pass through the rear section and enter threaded openings 24 in the body portion 10. It may also be noted that the rear sec-

tion of the lock is provided with a cut-away or recessed portion 25 adapted to receive the disk 15, so that the front face of the section 18 may fit snugly against the rear face of the section 10. It will also be noted that the hub 20 of the rollback fits snugly against the disk 15 and will rotate therewith and with the key barrel 12, all of these parts being rotatably associated with the respective casing sections.

As will be explained hereinafter, the basic body portion 10 of the lock may be used with parts other than the part 18, this latter part being employed when a rollback is to be used, and is employed with the basic section 10 and without other parts when a short cylinder is desired.

As shown in Fig. 6 of the drawing, a plurality of spacing elements may be employed between the sections 10 and 18 in order to increase the length of the cylinder lock. Three of these sections are shown in Fig. 6, but it will be understood that as many may be employed as is desired. The first of these sections, designated by the numeral 30, is shown in Fig. 10 of the drawing and is designed to be placed against the end of the section 10, as it is provided with a relatively large opening 31 to rotatably receive the disk 15, which, it will be recalled, is of larger diameter than that of the key barrel. When only one spacing section is employed it will be understood that the rear section 18 will be placed directly against the section 30, and the cylinder thus built will be as much longer than the one shown in Fig. 4 as the thickness of the section 30. It may also be noted that the thickness of this section will be the same as that of the disk 15, so that the parts will fit snugly together.

When, however, it is desired to provide a still longer cylinder, additional intermediate sections 32 may be employed, two of which are shown in Fig. 6. These sections are provided with openings 33 to receive spacing disks 34, which may be conveniently of the same diameter as the key barrel 12, and as they are of less diameter than the disk 15, the openings 33 will be smaller than the opening 31. The disks 34 will be of the same thickness as the spaced sections 32, and a further disk 34 may be employed, as shown in Fig. 6, to lie within the recess 25 of the section 18 and abut against the hub 20 of the rollback so as to properly space the latter from the rear end of the lock.

It will be understood that the spacing sections 30 and 32 are provided with openings 37 to receive screws 23 therethrough so as to secure all these sections to the section 10 by the same screws which are used to secure the rear section 18 in place. Also, the spacing disks 34 are provided with openings 38 which receive the screws 22 used to secure the rollback in place, and it will be seen that these openings will register with the openings 39 in the hub of the rollback through which these screws pass, and with openings 40 in the disk 15 (Fig. 9) which are threaded to receive the screws.

It will be apparent from Fig. 6 of the drawing that the cylinder lock built up of the various sections and assembled in the manner described will have substantially the same exterior appearance as a one-piece cylinder, but at the same time will be readily adjustable as to length, depending upon the number of the spacing sections employed between the body section 10 and the rear section 18. Moreover, the parts are readily detachable, it only being necessary to remove the screws 22 and 23 to release the sections of the lock casing, and also the spacing elements 34 and

rollback 21, from the key barrel. It will be understood, however, that when these parts are detached the disk 15 remains in place, being secured to the key barrel by the screws 14.

5 In Fig. 7 of the drawing I have shown a lock designed to be employed with a night latch or rim latch, for example. In this instance the front or basic portion 10 of the cylinder is employed, with the parts contained therein as previously described, including the disk 15 employed to hold the key barrel in place. Mounted against the face of the disk 15 is a second disk 41, of the same size as the disk 15, which is secured to the latter by screws 42 received in the openings 40. The disk 41 is provided with a rectangular opening 43, and also with an elongated or slot-like opening 44 to receive square and flat spindles, respectively, so that this structure may be used with a spindle of either form. In Fig. 7 of the drawing a flat spindle 45 is shown, with its end extending into the slot 44 so that the spindle will be rotated by the rotation of the key barrel. Also, as shown in Figs. 7 and 8 of the drawing, the body portion 10 of the lock is provided with threaded openings 46, extending through the cylindrical portion 17 of the body, which are adapted to receive screws (not shown) to mount the case upon the door.

30 The operation and construction of the above described parts are believed to be clear from the description given. It will be apparent, however, that I have shown a construction which may be employed to build a plurality of locks of different character upon a basic structure, the various constructions being the result of using with the basic structure one or more parts which are readily detached or assembled, and economically manufactured. Moreover, in any of the various forms shown the lock will give the appearance of being a unitary structure, and will operate as a unitary structure. Also, each of the sections 35 which are used with the basic portion 10, whether reference is made to the rear section 18 or the spacing sections 32, consists of a main section of substantially the same diameter as the cylinder 40 itself, and a disk portion or spacing disk rotatably mounted within such main section.

45 While I have shown and described some preferred embodiments of my invention, it will be understood that it is not to be limited to all of the details shown, but is capable of modification and variation within the spirit of the invention and within the scope of the claims.

50 What I claim is:

1. A cylinder lock comprising a cylindrical housing having tumblers therein, a key barrel 55 rotatably mounted in the housing, a plurality of sections detachably securable selectively at the rear face of said housing, each of said sections comprising a main portion secured to the housing, and conforming in outline thereto, a disk-like member rotatably mounted in said main portion and connected to the key barrel, and a lock-actuating element secured to said disks and to the key barrel.

60 2. A cylinder lock comprising a housing provided with tumblers and having a key barrel rotatably mounted therein, a member secured to the inner end of the key barrel to retain it in the housing, a rear section detachably secured to the rear end of the housing, a rollback rotatably mounted in said section on an axis coincident with that of the key barrel, means securing said rollback to said member, and a spacing section disposed between said housing and said rear section, said spacing section comprising a main 65

70 75

portion secured to the housing and a disk rotatable in said portion and secured to said member and to the rollback.

3. A cylinder lock comprising a housing provided with tumblers and a key barrel rotatably mounted therein, a disk secured to the inner end of the key barrel to retain it in place, a spacing member secured to the rear end of the casing and having an opening to rotatably receive said disk, a rear section comprising a main portion secured to the casing and having a recess, a second disk rotatably disposed in said recess and secured to the first disk, and a rollback having a head rotatably mounted in the rear section and secured to said disks.

4. A cylinder lock comprising a housing provided with tumblers and a key barrel rotatably mounted therein, a disk secured to the inner end of the key barrel to retain it in place, a spacing member secured to the rear end of the casing and having an opening to rotatably receive said disk, a rear section comprising a main portion secured to the casing and having a recess, a second disk rotatably disposed in said recess and secured to the first disk, a rollback having a hub rotatably mounted in the rear section and secured to said disks, and an additional spacing member between said first spacing member and the rear section, said additional spacing member comprising a main portion secured to the housing and an additional disk member rotatably mounted in the

main portion and secured to said other disks and to the rollback.

5. A sectional lock comprising a housing, a key barrel rotatably mounted therein, tumblers associated with said key barrel and housing to control the rotation of the key barrel, a plurality of spacing sections at the rear end of the housing, each of said sections comprising a main portion detachably secured to the housing and a disk-like member rotatable in said main portion and detachably secured to the key barrel, and an end section detachably secured to the housing and having a rollback rotatably carried thereby, said rollback being secured to said disk members and to the key barrel, and the thickness of said disk members being substantially equal to that of said spacing sections.

6. A cylinder lock comprising a housing provided with tumblers and having a key barrel rotatably mounted therein, a rear section detachably secured to the rear end of the housing, a rollback rotatably mounted in said section on an axis coincident with that of the key barrel, means securing said rollback to the key barrel, and a spacing section secured between said housing and rear section and conforming in outline with the housing, said spacing section comprising a main portion having an opening therein and a disk rotatably disposed in said opening, and said securing means passing through said disk.

SAMUEL OXHANDLER.
